COLOSTOMY DEVICE

Murle Perry, Minneapolis, Minn.

Application March 11, 1949, Serial No. 80,833

5 Claims. (Cl. 128—283)

1

This invention relates to stoma receivers which can be employed to permit irrigation of the intestinal tract to which the stoma is attached.

It is the general object of this invention to provide a novel and improved stoma receiver of cheap and simple construction which can be readily employed to permit thorough irrigation of the intestinal tract to which the stoma is attached.

A more detailed object is to provide such a stoma receiver including a ring which can be strapped to the body to fit around and receive a stoma, and a flexible bag which can be attached to the ring and which includes an apertured disc mounted opposite the aperture in the ring and through which a catheter may be inserted to be received in the stoma, flexibility of the bag permitting the disc to be engaged with the stoma as the catheter is inserted through the same to seal the outlet of the stoma and prevent the backflow of irrigating fluid until a desired quantity of fluid has been accumulated in the intestinal tract to which the stoma is connected.

A further object is to provide such a stoma receiver wherein the disc is made of transparent material forming a window permitting the stoma to be viewed during the irrigating operation.

The objects and advantages of the invention will more fully appear from the following description made in connection with the accompanying drawing wherein like reference characters refer to the same or similar parts throughout the various views, and in which

Fig. 1 is a view in front elevation showing the stoma receiver as it will appear with an irrigating catheter in use in connection therewith;

Fig. 2 is a vertical section taken on the line 2—2 of Fig. 1 as indicated by the arrows and showing the stoma receiver applied to the body and with an irrigating catheter inserted through the stoma into the intestinal tract of the body; and

Fig. 3 is a view in side elevation and with certain parts broken away and shown in section, illustrating the manner in which the outlet of the stoma is plugged by the disc to prevent backflow of fluid from the intestinal tract during the irrigation operation.

In accordance with the invention, there is provided a ring 4 having a stoma receiving aperture 5 in the ring 4, the bag 12 is provided with an opening 17

somewhat convexly formed so as to form a tight seal with the body of a human being surrounding a stoma A which, of course, is connected to the intestinal tract of the body. At its outer side and surrounding the opening 5 the ring 4 is equipped with a grooved circular flange 6, while carried by the ring 4 at its outer surface laterally at the two sides of the flange 6 are a pair of buttons 7 to which the slotted ends of a belt 8 may be attached. This belt is equipped with a buckle 9 to adjust the effective length of the belt, and by the medium of this belt the ring 4 may be held tightly in place on the body.

For use with the ring 4 there is provided a flexible bag 10 preferably formed of rubber or somewhat resilient plastic. This bag has at its upper portion a lateral mouth 11 carrying a reinforcing rib which can be attached to the grooved flange 6, the reinforcing rib having sufficient resiliency to tightly hold the mouth of the bag in sealed relation on the flange 6. In order that the mouth 11 of the bag 10 may be readily attached to and detached from the flange 6 the flange 6 is cut away at one portion 12 thereof as at the upper part at the point 12, and the ring 4 is provided with a channel 13 through its outer portion exterior of the point 12 whereby a finger can be run downwardly through this channel 13 to permit the finger to catch one edge of the mouth 11 of the bag to permit ready disengagement of the mouth from the rib by rolling the portion engaged by the finger over the cut away portion 12. The bag 10 is widened below its receiving portion and the lower part of the bag is provided with a number of vertical corrugations 14 permitting the bag to expand considerably as it fills. The lower part of the bag is reduced in width and forms an outlet neck 15. To close the outlet neck there is provided a rubber tube 16 which may be fitted into a bight formed in the outlet neck 15; and there is also provided a metal channel 26 of such size as to tightly receive a portion of the outlet neck 15 carried around the rubber tube 16. The arrangement provided forms a simple closure for the lower part of the bag and at the same time permits the lower part of the bag to be readily opened to dump the contents thereof.

Opposite the stoma receiving aperture 5 in the ring 4 the bag 12 is provided with an opening 17

and the bag is ribbed or reinforced at 18 adjacent the edge of the opening, the reinforcing rib 18 being elastic. A grooved disc 19 preferably made of transparent plastic or other transparent material fits within the opening 17, the peripheral groove formed in this disc receiving the rib 18 and the disc being thus connected in sealed relation to the bag 10. The disc 19 has a central opening 20 therethrough, this opening being slightly tapered from the exterior side of the disc 19 to the interior side thereof to at times receive a tapered plug 21 carried as by a cord 22 carried by the groove of the disc 19.

For use with the stoma receiver there is shown a tubular catheter 23 to which a flexible tube 24 is connected, it being understood that this tube 24 will be connected with a water supply and may be used for irrigating the intestinal tract B of the body after the catheter is inserted through the stoma A. The catheter 23 slidably carries an elastic ring 25 which will form sealing engagement with the catheter but it may be slid longitudinally of the catheter to vary the extension of the catheter beyond this ring.

Assuming that the stoma receiver is mounted on the body with the stoma A projecting into the upper portion of the bag 10 through the opening 5 in the ring 4, it is a very easy matter to employ the catheter 23 for irrigating the intestinal tract B of the body. Normally the plug 21 will close the opening 20 in the disc 19. When it is desired to irrigate, the plug 21 will be removed and the ring 25 carried by the catheter 23 will be set to determine the distance that it is desired to insert the catheter into the intestinal tract B of the body. While viewing the stoma A through the window formed by the transparent disc 19, the catheter 23 may be inserted through the opening 20 in the disc 19 and projected through the opening in the stoma A into the intestinal tract B. As the stoma can be viewed during this insertion operation no difficulty will be experienced in locating and inserting the forward end of the catheter properly. After the catheter is inserted, the disc 25 may be grasped by the fingers of one hand and while viewing the stoma A through the transparent window formed by the disc 19 the ring 25 may be pressed against the disc 19 to seal the opening 20 and thereupon the disc 19 may be carried into engagement with the outer portion of the stoma 18 as illustrated in Fig. 3 to seal the outlet of the stoma A. Thereupon the water or other irrigating fluid may be allowed to flow through the tube 24 and the catheter 23 into the intestinal tract B until the fluid has accumulated to a desired extent within the intestinal tract B and a slight pressure has been built up in this intestinal tract to thoroughly flush and clean the same. Of course, the flexibility of the bag 10 permits the disc to be brought into engagement with the stoma A after the catheter has been inserted. When at length sufficient water or other fluid has entered the body, the disc 19 may be allowed to move away from the stoma A, whereupon the fluid and other matter within the intestinal tract B may be allowed to dump into the bag 10. The lower end of the bag may be opened before or after this dumping operation so as to permit deposit in a proper receptacle. After the irrigation has taken place the catheter 23 will be removed, whereupon the plug 21 may be inserted in the opening 20.

It will be seen that a highly effective apparatus has been provided which will permit ready irrigation of the intestinal tract of a person having

a stoma and that the irrigation can be accomplished by the individual having the stoma without outside assistance. Heretofore, while in certain stoma receivers it has been possible to insert a catheter into the stoma through the receiver to permit irrigation, to my knowledge no practical structure which compares in simplicity to mine has been provided to close off the outlet of the stoma as the irrigation takes place to build up the accumulation of water or fluid within the intestinal tract and produce a thorough flushing action. The irrigation can take place without soiling the clothing or hands of the party.

It will, of course, be understood that various changes may be made in the form, details, arrangement and proportions of the various parts without departure from the scope of the present invention which, generally stated, consists in the matter shown, and described, and set forth in the appended claims.

What is claimed is:

1. A stoma receiver comprising a ring into the aperture in which a stoma may be projected, a flexible bag releasably connected to the outer side of said ring to receive from the stoma, said bag having an opening through its outer portion opposite the stoma receiving aperture in said ring, and an apertured disc mounted in the opening of the bag and through which an irrigating catheter may be passed into the intestinal tract through the stoma, the disc being capable of being pressed inwardly against the stoma through flexure of the bag as a catheter is inserted to seal the outlet of the stoma against backflow of fluid fed through the catheter into the intestinal tract until a desired quantity of fluid has been accumulated in the intestinal tract.

2. The structure defined in claim 1, said disc being formed of transparent material and forming a window through which the stoma may be viewed as the catheter is inserted through the stoma and as the disc is brought into engagement with the stoma.

3. A stoma receiver comprising a ring into the aperture in which a stoma may be inserted, a flexible bag releasably connected to the outer side of said ring, said bag having an opening opposite the stoma receiving aperture, an apertured disc mounted in the opening of the bag and through which an irrigating catheter may be passed through the stoma into the intestinal tract, the disc being capable of being pressed inwardly against the stoma through flexure of the bag as the catheter is inserted whereby the disc will seal the outlet of the stoma against backflow of fluid fed through the catheter into the stoma until the desired quantity of fluid has been accumulated in the intestinal tract, and belt attaching members carried by said disc, one at either side of the bag and to which a belt may be attached for mounting the receiver on the wearer's body.

4. The structure defined in claim 3, said belt attaching members comprising buttons.

5. A stoma receiver comprising a ring having a stoma receiving aperture therein and adapted to be placed against a wearer's body to surround a stoma received in said aperture, said ring having on its outer face a circular grooved flange, belt attachment buttons mounted on the outer side of said disc one at either side of said grooved flange, a flexible bag having a circular mouth at one side thereof near its top, said mouth being connectable to said grooved flange, said bag having an opening in its outer surface opposite

the stoma receiving aperture of said ring, an apertured disc received within said opening of the bag and through the aperture of which a catheter may be inserted through the stoma into the intestinal tract, the flexibility of said bag 5 permitting said disc to be carried against the stoma as the catheter is carried through the same to close the stoma against backflow of irrigating fluid transmitted through the catheter, and a removable plug for the aperture of said disc.
